(57) **CLAIM**

The ornamental design for a sacroiliac joint implant, as shown and described.

DESCRIPTION

FIG. 1 is a perspective view of a distal end of a sacroiliac joint implant in accordance with a preferred embodiment of the invention.

FIG. 2 is a perspective view of a proximal end of the sacroiliac joint implant of FIG. 1.

FIG. 3 is an elevational view of the sacroiliac joint implant of FIG. 1.

FIG. 4 is a plan view of the proximal end of the sacroiliac joint implant of FIG. 1; and,

FIG. 5 is a plan view of the distal end of the sacroiliac joint implant of FIG. 1.
